UNITED STATES PATENT OFFICE.

PAUL J. MARKS, OF ROCHESTER, NEW YORK, ASSIGNOR TO EASTMAN KODAK COMPANY,
OF ROCHESTER, NEW YORK, A CORPORATION OF NEW YORK.

PHOTOGRAPHIC SHUTTER.

1,214,699.

Specification of Letters Patent.

Patented Feb. 6, 1917.

Application filed September 27, 1915. Serial No. 52,879.

To all whom it may concern:

Be it known that I, PAUL J. MARKS, of Rochester, in the county of Monroe and State of New York, have invented certain new and useful Improvements in Photographic Shutters; and I do hereby declare the following to be a full, clear, and exact description of the same, reference being had to the accompanying drawings, forming a part of this specification, and to the reference-numerals marked thereon.

My present invention relates to photography and more particularly to photographic shutters and it has for its object to provide a pivoted blade shutter of the "set" type which will be strong and durable and simple in construction and operation.

The improvements are directed in part to the means whereby the blades are actuated by the driving or master member and the time mechanism which temporarily halts the driving member with the blades in open position for a time or bulb exposure. A convenient and novel means is also provided for adjusting these time stops.

To these and other ends the invention resides in certain improvements and combinations of parts all as will be hereinafter more fully described, the novel features being pointed out in the claims at the end of the specification.

In the drawings: Figure 1 is a front elevation of a shutter constructed in accordance with and illustrating one embodiment of my invention, the cover plate being removed to reveal the interior mechanism and the parts being in their normal position with the blades closed; Fig. 2 is a similar view showing the parts in set position; Fig. 3 is a fragmentary view of the same nature showing the releasing lever after it has been operated but before its return; Fig. 4 is a view corresponding to Fig. 3 with the releasing lever returned and the shutter held open; Fig. 5 is a fragmentary view showing the blade actuating parts in a position corresponding to that of Fig. 1 but with parts of the time mechanism removed; Fig. 6 is a similar view with the parts positioned to correspond with Fig. 2; Figs. 7 and 8 show the positions of certain parts when the shutter is in the condition shown in Figs. 3 and 4, respectively; Fig. 9 is a detail section taken substantially on the line 9—9 of Fig. 5; Fig. 10 is a detail section taken substan-

tially on the line 10—10 of Fig. 5, and Fig. 11 is a detail view of the driving spring and adjacent parts.

Similar reference numerals throughout the several figures indicate the same parts.

As before stated, the present shutter is a set shutter and in its complete form would include mechanism additional to that which will be herein described for effecting instantaneous or automatically timed exposures but such mechanism is not necessary to an understanding of the present invention and it has not been illustrated. It may be said, however, that this invention contemplates the use of the strong spring on the driving member of the instantaneous mechanism for effecting the time exposures as well, although it is usually considered necessary to provide a separate lighter spring for the time mechanism.

Referring more particularly to the drawings, 1 indicates a circular casing having a partition plate 2 and a central exposure aperture 3 normally closed by the blades 4. As best shown in Figs. 1, 9 and 10, the blades turn on pivots 5 fixed in the shutter casing and are provided with actuating pins 6, 7, 8 and 9 which are secured in the usual blade actuating ring 10 slidable in a depressed portion 11 in the rear or bottom wall of the casing so that all of the blades are opened and closed together.

Fixed to the partition 2, preferably at the top of the casing, is a stud 12 on which turns a disk 13 having a hub 14. The disk is provided with a shoulder 15, a cam face 16 and has secured against the top face thereof by a screw 17 a semi-annular spring latch 18 capable of being deflected upwardly and furnished with a guide pin 19. The inner end of a flat spiral or clock spring 20 (Fig. 11) the outer end of which is fixed to the partition or casing at 21, is secured to a drum 22 surrounding the hub 14 and having a flange 22^a or circular plate overlying the disk 13. The plate 22^a is locked to the disk 13 to turn therewith by reason of an aperture 23 therein that engages over the head of the screw 17 and thus the hub 14 and drum 22 are locked together. They are turned against the tension of the spring 20 by a setting lever 24 which locks against flat faces 25 on the end of the drum 22 and is held in place by a cap screw 26.

The shutter releasing lever is indicated

at 27 and is pivoted at 28 to project to the exterior of the casing. Preferably integral therewith is a detent arm 29 which, when the spring 20 is wound up by moving the setting lever 24 to the left, engages with the shoulder 15 on the disk 13. The blade actuating pin 9 is beveled, as shown in Fig. 9, and during this setting movement just referred to, the downwardly turned and preferably beveled end of the spring latch 18 shown in the same figure, rides over the said pin from the position of Fig. 5 to that of Fig. 6 and the blades remain closed. When the lever 27 is rocked to release the shoulder 15 from the detent 29, the disk 13 moves to the right under the influence of the spring 20 and the cam face 30 at the end of the latch 18 engages the pin 9 and displaces it to the left as shown in Fig. 7 which is the direction that causes the shutter blades to open. By the time the downwardly turned end of the latch has passed the pin, as in Fig. 9, the latter is free to return which it does upon the continued movement of the spring driven disk 13 when the cam face 16 on the latter comes in contact with the other blade actuating pins 8, as shown in Fig. 8. This pin 8 and, in fact, each pin operates in a slot 31 in the partition 2 and when the blades are closed, it abuts the end of the slot while the cam 16 is still in contact with it. In this way, the pin 8 halts the return movement of the spring driven disk 13 and constitutes the ultimate stop therefor.

I have so far described the complete opening and closing movement of the shutter throughout the range of movement of the driving or master member under the influence of the spring 20, but for time and bulb exposures, this movement is divided into two periods in the following manner: The plate 22^a is formed with a laterally extending projection 32 in the path of which there normally lies, when the shutter is set as in Fig. 2, an abutment 33 on the short arm 34 of a lever 35 pivoted at 35^a to the partition 2. The long arm 36 of this lever is arranged to be engaged at 37 by either one of two time stops 38 and 39 pivoted at 40 and 41, respectively, and normally held in the path of the arm by springs 42 and 43. When the shutter releasing lever 27 is pressed to release the driving member, an arm 44 thereon depresses an arm 45 on the latch 39 and moves the latter to inoperative position, as shown in Fig. 3. The driving member being released by the same movement, the projection 32 on the plate 22 strikes the abutment 33 on the lever 35 and rocks it until it is halted by the stop 38, as also shown in Fig. 3. The driving member is therefore detained in the position of Fig. 7 while the shutter blades are open, the latch 18 having thrust the blade actuating

pin 9 to the extreme left but not having released it, while the cam face 16 is not yet in contact with the other pin 8. Upon the next actuation of the releasing lever 27 or, more properly, upon its return movement under the influence of its spring 46 acting against a fixed pin 47, the arm 44 thereon leaves the arm 45 allowing the stop 39 to return to its operative position under the influence of its spring 43 and by engaging an arm 48 on the stop 38, moves it to inoperative position against the tension of its spring 42 and the long arm 36 of the lever 35 transfers its engagement to the stop 39, as shown in Fig. 4. The movement of the driving member during this transfer is only that indicated by a comparison of Figs. 7 and 8 and hence the shutter blades are not effected and remain open. Upon depressing the lever 27 again, however, the stop 39 is again moved out of engaging position in the same manner by the arm 44 and the arm 36 of the intermediate lever 35 is free of both stops and turns until it permits the projection 32 to ride off of the abutment 33, as shown in Fig. 1. The driving member is therefore free to complete its driving movement and as the cam 16 thereon immediately engages the shutter actuating pin 8 and moves it to the left the blades are closed and the driving member halted by the pin 8, as shown in Fig. 5.

It will be noted that the impact of the driving member through the projection 32 is taken by the short arm of the lever 35 and the latter is halted by the relatively delicate time stops 38 and 39 at the end of its long arm. These stops therefore do not receive the full hammering action of the driving member as the latter is acting against a mechanical disadvantage of leverage in communicating its power to the stop.

The cycle of movement just described is, as stated, that of a time exposure requiring two actuations of the releasing lever 27. When it is required to make a bulb exposure wherein the shutter is opened by the movement of the said lever to the left and closed by its return, the stop 39 is thrown out of action by rotating a controlling ring 49 mounted on the exterior of the casing 1. A second arm 50 on the stop 39 projects through an opening 51 into a recess 52 in the said ring during time exposures and does not impede the movements of the stop, as shown in the figures. When the ring is rotated, to carry this recess 52 beyond the arm 50, the latter is engaged by the solid portion of the ring and the stop held in an inoperative position corresponding to that shown in Fig. 1. Thus, the lever 35 is free immediately upon the return of the releasing lever 27.

It will be noted from an inspection of Fig. 5 that the driving member securely holds the

the shutter blades closed before the shutter is set by engagement of the cam 16 with the pin 8 and there is no danger of their being jarred open.

5 I claim as my invention:

1. In a photographic shutter, the combination with shutter blades and an actuating pin therefor, of a driving member provided with a spring latch adapted to ride over the actuating pin when the driving member is moved in one direction and to displace the pin and actuate the blades when the driving member is moved in the other direction.
- 5 2. In a photographic shutter, the combination with shutter blades and an actuating pin therefor having an inclined end face, of a rotary driving member provided with a spring latch adapted to ride over the actuating pin when the driving member travels in one direction and having a cam faced end portion adapted to displace the pin laterally and actuate the blades when the driving member is moved in the other direction.
- 20 3. In a photographic shutter, the combination with shutter blades and an actuating pin therefor, of a driving element or master member arranged to operate the pin, the latter also serving as a stop for finally arresting the driving movement of the element.
- 35 4. In a photographic shutter, the combination with a partition plate having a slot therein and shutter blades adjacent thereto, of an actuating pin for the shutter blades projecting through the slot in the plate and a driving element or master member arranged to operate the pin, the latter being adapted to abut against the end of the slot and serve as a stop for finally arresting the driving movement of the element.
- 40 5. In a photographic shutter, the combination with a driving or master member and a time stop, of a lever having a short arm to receive the impact of the driving member and a long arm adapted to engage the time stop.
- 45 6. In a photographic shutter, the combination with a driving or master member and a movable time stop for temporarily arresting the movement thereof, of a detent for holding the driving element in set position and adapted to also control the time stop.
- 50 7. In a photographic shutter, the com-

bination with a driving or master member and a movable time stop for temporarily arresting the movement thereof, of a releasing lever having one arm constituting 60 a detent for the driving member to hold it in set position and another arm arranged to control the time stop.

8. In a photographic shutter, the combination with a driving element or master member, and a time stop, of a lever having a short arm to receive the impact of the driving member, a long arm adapted to be arrested by the time stop and an abutment engaged by the master member when the latter is reset to return the lever.

9. In a photographic shutter, the combination with a driving element or master member, and a pair of time stops, of an intermediate member arranged to take the 75 impact of the driving element and to be itself arrested by the time stops, and a releasing lever acting as a detent for the driving member and provided with an arm controlling the time stops to arrange them alternately in the path of the intermediate member upon successive operations of the releasing lever.

10. In a photographic shutter, the combination with a driving element or master member an intermediate member arranged to take the impact of the driving element and a pair of spring actuated time stops both of which are normally in the path of the intermediate member, of a releasing lever 90 acting as a detent for the driving member and provided with an arm coöperating with the time stops to move one of them out of the path of the intermediate member when the releasing lever is operated to free 95 the driving member and to so move the other one when the releasing lever returns.

11. In a photographic shutter, the combination with a circular shutter casing, a driving or master member, an intermediate 100 member arranged to take the impact of the driving member and two time stops arranged to alternately engage and arrest the intermediate member, of a controlling ring mounted to revolve on the periphery of the 105 casing and adapted to engage one of the time stops to hold it in inoperative position.
